DOOR LATCH

John H. Roethel, Detroit, Mich.

Application January 22, 1940, Serial No. 314,991

15 Claims. (Cl. 292—340)

This invention relates generally to door latches and particularly, although not exclusively, to latch devices adapted for use in connection with the doors of automobiles and other vehicles. The invention contemplates the provision of an improved device of this class including lock mechanism adapted to be installed upon the swinging door of the automobile or vehicle body, an improved striker or keeper mechanism cooperable with the latch bolt and adapted to be installed on the body post or pillar, and improved means associated with the latch bolt and striker or keeper mechanism for holding the door firmly in position against transverse and vertical movements during operation of the vehicle. An object of the invention is to provide an improved device of the above class or type which is relatively simple and compact in construction, economical to manufacture, durable and efficient in use and which in operation is also capable of providing an easy, relatively quiet, and positive closing door, a particularly important objective in connection with the steel doors of automobiles.

A further object of the invention is to provide an improved latch bolt and striker or keeper device which in efficient and simple manner combines the functions heretofore accomplished in separate striker or keeper device and dovetail units and which in addition permits simplification of the latch bolt mechanism mounted upon the door.

Another object of the invention is to provide an improved striker unit adapted to be mounted upon the body pillar or post and having a spring pressed striker member adapted normally to extend downwardly into the path of a longitudinally extending normally non-retractable latch bolt and adapted to be depressed or forced upwardly by the bolt, when the door is closed, thereby permitting the bolt to pass the striker and engage an inclined or tapered face thereof, firm and tight engagement of the bolt with the final locking step of the striker member being ensured under all conditions by means of yielding wedging means whereby the door is held rigidly against chattering or vibratory motion during operation of the vehicle.

A further object of the invention is to provide an improved latch bolt and striker device embodying a normally non-retractable latch bolt, a vertically movable striker member adapted to project downwardly into the transverse path of movement of the bolt, and yieldable wedge means associated therewith and cooperable with the latch bolt and striker member to hold the door against

vertical and transverse movements during operation of the vehicle, the improved construction being such as to provide a simple, compact and inexpensive mechanism producing an easy and quiet closing door which will be held firmly and positively under operating conditions of the vehicle.

A further object is to provide means associated with a latch bolt of the type which is non-retractable by engagement with the striker, which means 10 will either prevent the bolt from being locked or dogged, when the door is open, against retraction by turning the door handle or will kick out the bolt dogging device when the door is closed and the bolt engages the striker.

Another object of the invention is to provide a striker assembly adapted to be mounted upon the door post or pillar and embodying a movable striker member, such as a vertically slideable striker member, mounted to extend generally vertically into the path of a normally stationary longitudinally extending latch bolt and in which the striker member includes in one unit successive safety and final locking portions or steps adapted to be engaged by the latch bolt, the latter being 25 retractable only when opening the door.

Another object of the invention is to provide a striker assembly in which the striker member includes a safety locking step and a final locking step successively engaged by the bolt, the safety locking step being shifted by the bolt relatively to the final locking step and the striker member being shifted as a unit upon engagement of the bolt with the final locking step as the door is closed.

Still a further object is to provide an assembly or device of the foregoing character in which the door may be closed without slamming and with a minimum of effort and quietness, making it unnecessary to cause the bolt to retract when closing 30 the door and permitting the door to be readily opened by turning the handle to retract the bolt sufficiently to clear the striker member or members, thereby permitting the end of the latch bolt to pass thereby as the door is pulled open.

Other objects of this invention will appear in the following description and appended claims, reference being had to the accompanying drawings forming a part of this specification wherein like reference characters designate corresponding parts in the several views.

Fig. 1 is a fragmentary side elevation of a portion of an automobile body in which the present invention is incorporated in connection with the doors thereof.

Fig. 2 is an enlarged vertical section taken

substantially through lines 2—2 of Fig. 1 looking in the direction of the arrows.

Fig. 2a is a fragmentary view similar to Fig. 2 but illustrating a slight modification in the striker member.

Fig. 3 is a section taken substantially through lines 3—3 of Fig. 2 looking in the direction of the arrows.

Fig. 4 is a section taken substantially through lines 4—4 of Fig. 2 looking in the direction of the arrows.

Fig. 5 is a section taken substantially through lines 5—5 of Fig. 2 looking in the direction of the arrows.

Fig. 6 is a fragmentary view, partly in section and in part similar to Fig. 2, illustrating another embodiment of striker member.

Fig. 7 is a horizontal section taken substantially through lines 7—7 of Fig. 3 looking in the direction of the arrows.

Fig. 8 is an exploded view, in perspective, illustrating the adjustable mounting for the striker assembly on the body post or pillar.

Fig. 9 is an inner face view, in elevation, illustrating one embodiment of the latch bolt unit.

Fig. 10 is a section taken substantially through lines 10—10 of Fig. 9 looking in the direction of the arrows.

Fig. 11 is a fragmentary view, similar to Fig. 9, illustrating the kick-out or throw-out position of the split latch bolt.

Fig. 12 is a view similar to Fig. 9 but illustrating a second embodiment of latch bolt unit.

Fig. 13 is a fragmentary outer end elevation of the structure shown in Fig. 12.

Fig. 14 is a section taken substantially through lines 14—14 of Fig. 12 looking in the direction of the arrows.

Fig. 15 is a fragmentary view similar to Fig. 12 but illustrating the kick-out or throw-out position of the split latch bolt.

Fig. 16 is a section taken through lines 16—16 of Fig. 12 looking in the direction of the arrows.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

In the drawings there are illustrated, by way of example, several embodiments of the present invention as applied to an automobile body B having swinging doors D hinged at their remote edges so as to swing together against a common body post or pillar B', the mechanism of the present invention comprising a latch bolt device mounted upon the door and a striker or keeper device mounted upon the body pillar or post at the jamb face of the door opening.

Referring particularly to Figs. 2 to 5, inclusive, the striker or keeper device, which is mounted upon the fixed body pillar or post, comprises a backing plate 20 offset centrally to extend through an opening in the pillar jamb 21, the offset portion providing upper and lower walls 20a and 20b, respectively, and the backing plate having upper and lower attaching flanges 20c lying against the outer face of the pillar jamb

21. The striker device also comprises outer upper and lower face plate portions 22 and 23 which are spaced apart, as shown in Fig. 2, for the passage therebetween of the latch bolt and wedge or guide member extending from the edge of the swinging door. The face plate portions 22 and 23 have countersunk holes 22a and 23a for the reception of fastening screws 24.

Within the upper casing formed by the members 22 and 20 is a compound striker or keeper member 25 which is slidably mounted within the casing. The striker member is provided with curved or arcuate inner and outer upright edges 25a and 25b which engage and slide upon correspondingly curved walls 26 and 27 formed from the backing plate 20. Thus, the striker member may slide up and down within the casing in a curved path corresponding to the curvature of the casing walls 26 and 27. The striker member has a hole or recess 29 within which is lodged the lower end of a compression spring 28 anchored at its upper end on the casing, the spring functioning to urge the striker member to its lower position as shown in Fig. 2. Vertical movement of the striker member is limited by means of a tongue 30 struck in from the backing plate and carrying upper and lower rubber bumpers 31 slidable within a recess 32 in the back wall of the striker member.

The striker member 25 is adapted to project downwardly below the wall 22 and is formed with a projecting wedge shaped step 33 which normally extends into the path of the latch bolt. The locking step 33 has a tapered or inclined edge 33a facing outwardly and also having an inner tapered edge or face 34. In the device of Fig. 2 the edge 34 terminates in a shoulder 35, whereas in Fig. 2a the shoulder is omitted and the striker step relieved at 34a at this locality. The bolt 36 is adapted, as the door is closed, to engage the edge or face 33a and elevate the striker member against the effort of the spring 28, and when the bolt passes the step 33 its inclined face 36a firmly and smoothly engages the correspondingly inclined face 34 of the locking step. When the bolt is fully home the striker member will be extended to bear against the full length of the inclined bolt face 36a.

The striker 25 not only comprises the final locking step 33 but also a first or safety locking step 38 which is carried by the striker body 25 and in the present embodiment is independently yieldable or retractable relatively thereto. The safety step 38 is in the form of a plunger set at an angle with respect to the body of the striker member and presenting outer and inner inclined faces 38a and 38b, respectively, forming a wedge extending normally into the path of the latch bolt 36. The plunger 38 extends upwardly through a hole 37 which terminates within the body of the striker member and opens through the bottom face 33a thereof. Rubber bumpers 39 are secured to opposite faces of the plunger 38 by a cross pin 40, the bumpers extending laterally into slots 41 which communicate with the hole 37. A compression spring 42 engages the inner or upper end of the plunger and is confined within a counter-bore 43 in the striker body.

The bottom casing formed between members 23 and 20 partially houses a wedge shaped slide block 44 which has a limited sliding movement upon the bottom inclined wall 20b of this casing. The rear end of the block has a hole or bore 45 within which is mounted a compression spring

46 which is interposed between the block and the back wall of the casing. The block is held within the casing and limited as to its outward movement through the medium of a tongue or flange 47 on the casing which extends into a notch or recess 48 in the block. The upper wall 44b of the wedge block is exposed for engagement by a wedge member 49 secured to the edge of the door at a point below but outwardly of the bolt 36. The dovetail wedge 49 has an inclined lower face 49a which rides upon the upper inclined face 44b of the slide block, and as the door is closed the wedge member 49 will, as it passes into the space between the upper and lower casings, force the block 44 inwardly against the action of the spring 46, thus tending to lift the door and through the cooperative action of the bolt 36 against the face 34 of the striker step 33 clamping the door rigidly between the block 44 and the striker member 25. Since the block 44 is continuously urged outwardly by its spring 46, thereby tending to raise the wedge member 49, any play between the bolt and striker face 34 when the latter is forced home to its lowermost position will be taken up by outward movement of wedge 44. Thus, any play between the bolt and striker which will cause rattling or chattering when the door vibrates vertically will immediately be taken up and the door held tightly against vertical movement by the wedge 44 moving outwardly under the influence of the spring.

In Figs. 7 and 8 there is shown a mounting means by which the striker assembly may be adjusted transversely or horizontally with respect to its supporting post or pillar B'. The metal of the Jamb 21 of the pillar is pressed or stamped to provide a loop or strap-like retainer portion 50 through which may be slide an adjusting bar 51 having a fluted gripping face 52 engageable with the inner face of the pillar and also having holes 53 adapted to line up with adjusting slots 54 in the pillar. The attaching screws 24 for the striker assembly extend through the slots 54 and the tapped holes 53 in the adjusting bar, and by loosening the screws the striker assembly may be shifted bodily in conjunction with the bar 51 a distance equal to the distance that the screws 24 are adjustable in the slots 54. In Fig. 8 a center pillar B' of an automobile body is shown in which a striker assembly is adapted to be mounted at opposite faces of the pillar for the front and rear doors.

Referring to Fig. 6, there is shown a second embodiment of the striker or keeper device which comprises a backing plate 200 having an upper casing 56 secured thereto and housing a compound striker member 55 which is mounted for sliding movement at an oblique angle against the inner angular wall 56a of the casing. The striker block 55 is provided with a through slot 57 and a groove or blind slot 58 forming a continuation of slot 57 only at the back side of the block. Guide pins or studs 59 and 60 extend into the slots and are secured to the backing plate. The pin 59 extends the full depth of the slot 57 whereas the pin 60 extends partially into the slot 57 so as to ride into the shallow extension 58 thereof. In the lowermost position of the striker 55 the pin 59 is adapted to engage a rubber bumper 51a. The striker member is urged or moved to its lowermost position, as shown in Fig. 6, by a compression spring 61 extending into a hole 62 in the striker member and engaging the upper wall of the casing. The 75

striker 55 has a final locking step 55a and a safety locking step 55b projecting downwardly into the path of the bolt 36, there being a clearance space 55c between the steps which prevents engagement of this portion of the striker member with the upper end of the bolt. The steps 55a and 55b have inclined or tapered locking faces which are parallel to the face 36a of the bolt so that the bolt will engage a considerable area of the locking step when in either safety or final locking position. The embodiment of Fig. 6 includes the yieldable wedging means 44, 49 as shown in Fig. 2.

If desired, in order to ensure smooth action of the block 55 and to avoid any cramping action when the bolt engages inclined face 55c to elevate the block, the spring 61 may be centered, or approximately so, with respect to the block and a guide pin similar to pin 59 and cooperating slot, similar to slot 57, provided at the opposite side of the spring. The block in such instance would be guided at three points.

Referring particularly to Figs. 9 to 12, inclusive, the latch bolt device C in this instance comprises a case plate 63 terminating at its outer edge in a lateral flange 63a having an opening through which slidably extends the bolt 36, the dovetail wedge member 49 being secured by screws to the flange 63a at a point just below and outwardly 30 of the bolt 36. The case plate 63 has suitable screw bosses by which it may be secured by screws to the inner lock panel of the door. The rear end of the bolt 36 is engaged by one end of a spiral return spring 64, the opposite end of the spring being secured to the case plate. Riveted to the inner end of the bolt is a slide plate 65 having a horizontal guide slot 65a through which extends a guide stud 66 riveted to the case plate. The latch device of Fig. 9 is designed for the front door of an automobile body and also so that it may be locked with a key from the outside of the door. The bolt is remotely controlled from the inner side of the door through the medium of a link 67 having a lost motion slot 68 through which 45 extends a stud 69 secured to the inner side of the slide 65. The end of the remote control link 67 is connected to the inner door handle 70 in the usual manner. The outer door handle 71 has its shaft entered within a square opening 71a in the hub of a roll back 72 which engages a turned flange on the slide plate 65 so that by turning the outer handle 71 the roll back is partially rotated to retract the latch bolt independently of the inner door handle 70. The latter also may be turned 50 to retract the slide 65 and the latch bolt 36 against the action of the return spring 64.

The latch C has incorporated therein a conventional type unit 73 by which the roll back may be dogged or locked against rotation by key controlled means. When the key is turned in the lock from the outside of the door it will raise a dog 74 into abutting engagement with a lug 72a on the roll back, thus preventing the bolt from being retracted by turning the outer door handle 71.

The bolt 36 may be locked against retraction through operation of either of the handles by means of a push and pull device at the inner side of the door. This device comprises a plunger 75 having a knob at its upper end, the plunger extending through a hole in the garnish molding and pivotally connected at its lower end to a slide 76. This slide has a guide slot 77 for a stud 78 riveted to the case plate 63, and also a similar guide slot 77a for the stud 66. The slide 76 at its

lower end terminates in a dogging device 78 adapted to be forced downwardly by pushing down on the plunger 76 into position to abut a flange portion 80 on the bolt slide plate 85, thus preventing the latter from being shifted to retract the bolt.

In the present instance there is provided kicker means associated with the bolt and controlled by the striker for kicking out or shifting upwardly the dogging device 78 so as to move it out of locking position with respect to the slide 85.

The latch bolt, in the form herein shown, is constructed as a split bolt comprising the main portion 36 and a vertically movable portion 81 having flat contacting faces as shown in Fig. 10. The bolt portion 81 extends rearwardly of the portion 36 and terminates in an upper end extension 81a underlying a projecting flange or lug 84 on the slide 76. The bolt member 81 also has a lower rear end extension 83 engaged by the upper outer end of a spiral spring 82 secured at its inner end to the case plate. The outer working end of this spring has vertically spaced retainer grooves or notches 82a and 82b within which the rounded end of the extension 83 will fit and be yieldingly held by the spring which at all times exerts pressure thereagainst. It will be understood that member 81 extends through a slot communicating with the slot in the case plate through which bolt 36 extends. The main bolt portion 36 has a stud 85 upon which the bolt portion 81 is pivoted. It will be seen that the bolt kicker member 81 may be rocked about its pivot 85, as shown in Fig. 11, thereby raising its end 81a against the lug 84 and shifting the slide 76 upwardly so that the dogging portion 78 will be shifted out of the path of the portion 80 of the lock bolt slide 85.

In this operation the extension or finger 83 will be forced out of notch 82a and will snap into notch 82b, whereby the kicker 81 will be yieldingly held by the spring in the position of Fig. 11 with the outer end of the kicker flush with the end of the bolt 36. Thus, when the door is closed with the kicker 81 in the position of Fig. 9 and the dog 78 in bolt locking position, engagement of the bolt with the striker member will cause the latter to depress the outer end of the bolt kicker member 81 to the position shown in Fig. 11, thus forcing the slide 76 out of locking position with respect to the latch bolt slide 85. The kicker member will at all times remain in this position except when the slide 76 is pushed down. If the door is in closed position and the slide 76 pushed down, see Fig. 9 and Fig. 2a, the relieved portion 34a of the striker step 33 will permit the outer end of the kicker to be elevated, as the kicker is rocked, and permit the finger 83 to be forced from notch 82b of the spring to notch 82a.

In the embodiment illustrated in Figs. 12 to 16, inclusive, the latch bolt mechanism is substantially the same as the construction in Figs. 9 to 12, inclusive, with the exception principally that the latch bolt kicker member is vertically slidable instead of pivoted, the arrangement in this instance being such that the dogging slide 76 will at all times be shifted to inoperative position at any time that the door is open. In this embodiment the kicker member 86, which forms a portion of the slide latch bolt and normally extends face to face and flush with the main bolt member 36, is provided with two vertically extending guide slots 87 for the reception of pins or studs 88 carried by the bolt member 36.

Thus, the member 86 is mounted upon the bolt member 36 for limited vertical sliding movement. The member 86 in rear of the bolt has an offset 89 and an end extension 90 in line with the bolt 36 which underlies the lug 84 on the dogging slide 76. The kicker slide 86 is normally urged to the position shown in Fig. 15 by means of the light spiral spring 82 which is mounted concentrically with the main spring 84 and secured to the same struck-out portion of plate 83, there being a spacer disk 93 between the two springs, see Fig. 16. From the foregoing it will be seen that, when the door is open and the latch bolt out of engagement with the striker, the kicker slide 86 will be held in its raised position shown in Fig. 15 by the spring 82, the effort of the spring being sufficient to force the dogging slide 76 upwardly to its inoperative position. When, however, the door is closed, engagement of the latch bolt portions 36 and 86 with the striker member will force the member 86 down to its flush position with bolt member 36 as shown in Fig. 2, also Figs. 12 and 13. In the fully closed position of the door the shoulder 35 on the striker step 33 will overhang the bolt kicker member 86 and hold it out of action with respect to the dogging slide 76, thus permitting the latter to be pushed down to the locking position shown in Fig. 12. It will be understood that the bolt kicker member 86 operates within a slot 91 in the case plate flange 63a, as shown in Fig. 13.

With the use of a door latch having the pivoted kicker or throw-out member 81 of Fig. 9, it will be seen that closing of the door will cause the striker to rock the member 81 and throw out or kick out the dogging slide 76, assuming the latter has been pushed down. When the door is fully closed the kicker member 81 remains in kick-out position (Fig. 11) by reason of the spring notch 82b holding the finger 83. Thus, this construction precludes the possibility of closing the door from the outside and leaving the dogging slide 76 in locked position. The construction in Fig. 12 attains a similar result, also precluding the possibility of closing the door from the outside with the slide 76 in locked position. In this embodiment, however, the slide is always in its up or inoperative position whenever the door is open and the latch bolt out of contact with the striker.

I claim:

1. A striker device for use in cooperation with a latch bolt and in association with a swinging door hinged at one edge to a frame structure, comprising a casing, a striker member slidable on the casing in an up and down curvilinear path, and yieldable bolt latching step carried by said member and normally projecting into the path of the bolt.
2. A striker device for use in cooperation with a latch bolt mounted upon a swinging door hinged at one edge to a frame structure, comprising a pair of striker members normally projecting downwardly into the path of the bolt, one member being yieldingly slidable upon the other and the latter being yieldingly slidable in an up and down path angular with respect to the plane of the door.
3. A striker device for use in cooperation with a latch bolt mounted upon a swinging door hinged at one edge to a frame structure, comprising a striker member having a bolt latching step normally projecting into the path of the bolt, means for guiding said member for up and

down sliding movement angularly with respect to the plane of the door, spring means urging said member toward the bolt, wedge means on the frame structure movable in the direction of closing of the door under the influence of a projecting guide member on the door, and spring means urging said wedge means in the opposite direction to tighten the bolt against the striker member.

4. A striker device for use in cooperation with a latch bolt and in association with a swinging door hinged at one edge to a frame structure, comprising a casing, and a striker member slideable on the casing in an up and down curvilinear path and having a bolt latching step, and a second bolt latching step slideable independently in said member.

5. A striker device for use in cooperation with a latch bolt and in association with a swinging door hinged at one edge to a frame structure, comprising a casing, a striker member slideable on the casing in an up and down curvilinear path, a yieldable bolt latching step carried by said member and normally projecting into the path of the bolt, and means for tightening the bolt against said striker member substantially independently of said step.

6. A striker device for use in cooperation with a latch bolt and in association with a swinging door hinged at one edge to a frame structure, comprising a casing, a striker member slideable on the casing in an up and down curvilinear path and having a bolt latching step, a second bolt latching step slideable independently in said member, and means for tightening the bolt against said first latching step substantially independently of the second latching step.

7. A striker device for use in cooperation with a latch bolt mounted upon a swinging door hinged at one edge to a frame structure, comprising two bolt latching steps normally projecting into the path of the bolt and spaced apart in the direction of closing of the door, means for supporting said steps for bodily up and down curvilinear movement relatively to the bolt, spring means urging said steps toward the bolt, and means for tightening the bolt against one of said steps in the closed position of the door.

8. A striker device for use in cooperation with a latch bolt and in association with a swinging door hinged at one edge to a frame structure, comprising a casing, a member movable bodily on the casing in an up and down curvilinear path, spring means resisting movement of the member in one direction, said member having 55 two spaced bolt latching steps.

9. A striker device for use in cooperation with a latch bolt and in association with a swinging door hinged at one edge to a frame structure, comprising a casing, a member movable bodily on the casing in an up and down curvilinear path, spring means resisting movement of the member in one direction, said member having two spaced bolt latching steps, one step being yieldable relatively to the other.

10. A striker or keeper device for use with a door latch bolt, comprising a member having a bolt latching step, means for supporting said member for bodily movement in an up and down curvilinear path, and a second bolt latching step movable relatively to the first step and mounted on said member.

11. A striker device for use in cooperation with a latch bolt and in association with a swinging door hinged at one edge to a frame structure, comprising a casing, and a striker member slideable on the casing in an up and down curvilinear path and having a bolt latching step normally projecting into the path of the bolt.

12. A striker device for use in cooperation with a latch bolt and in association with a swinging door hinged at one edge to a frame structure, comprising a casing having spaced upwardly extending similarly curved walls, and a spring pressed striker member having similarly curved edges slidably bearing upon said walls.

13. A striker device for use in cooperation with a latch bolt, comprising a casing, and a striker member slideable bodily on the casing in an up and down curvilinear path and having a bolt latching step normally projecting into position to engage the bolt.

14. A striker device for use in cooperation with a latch bolt, comprising a casing, a striker member slideable bodily on the casing in an up and down curvilinear path and having a bolt latching step normally projecting into position to engage the bolt, and yieldable means engaged by a member independently of the bolt for tightening the bolt against said step.

15. A striker device for use in connection with a latch bolt and in association with a swinging door hinged at one edge to a frame structure, comprising a casing, a striker slideable on the casing in an up and down curvilinear path and including a bolt latching step normally projecting into the path of the bolt, and means for tightening the bolt against said step when the door is closed.

JOHN H. ROETHEL.
